(57) **CLAIM**

The ornamental design for a bicycle, as shown and described.

DESCRIPTION

FIG. 1 is a top, front, and left side perspective view of a bicycle embodying my new design;

FIG. 2 is a front and right side perspective view thereof;
FIG. 3 is a bottom, rear, and right side perspective view thereof;

FIG. 4 is a left side elevation view thereof;

FIG. 5 is a right side elevation view thereof;

FIG. 6 is a front elevation view thereof;

FIG. 7 is a rear elevation view thereof;

FIG. 8 is a top plan view thereof;

FIG. 9 is a bottom plan view thereof;

FIG. 10 is an enlarged and partial perspective view of area 10 in FIG. 1;

FIG. 11 is an enlarged and partial perspective view of area 11 in FIG. 1;

FIG. 12 is an enlarged and partial perspective view of area 12 in FIG. 1;

FIG. 13 is an enlarged and partial perspective view of area 13 in FIG. 1;

FIG. 14 is an enlarged and partial perspective view of area 14 in FIG. 1;

FIG. 15 is an enlarged and partial perspective view of area 15 in FIG. 1;

FIG. 16 is an enlarged and partial perspective view of area 16 in FIG. 2;

FIG. 17 is an enlarged and partial perspective view of area 17 in FIG. 2;

FIG. 18 is an enlarged and partial perspective view of area 18 in FIG. 2;

FIG. 19 is an enlarged and partial perspective view of area 19 in FIG. 2;

FIG. 20 is an enlarged and partial perspective view of area 20 in FIG. 2;

FIG. 21 is an enlarged and partial perspective view of area 21 in FIG. 3;

FIG. 22 is an enlarged and partial perspective view of area 22 in FIG. 3;

FIG. 23 is an enlarged and partial perspective view of area 23 in FIG. 3;

FIG. 24 is an enlarged and partial perspective view of area 24 in FIG. 3;

(Continued)

FIG. 25 is an enlarged and partial perspective view of area 25 in FIG. 3;
 FIG. 26 is an enlarged and partial perspective view of area 26 in FIG. 4;
 FIG. 27 is an enlarged and partial perspective view of area 27 in FIG. 4;
 FIG. 28 is an enlarged and partial perspective view of area 28 in FIG. 6;
 FIG. 29 is an enlarged and partial perspective view of area 29 in FIG. 6;
 FIG. 30 is an enlarged and partial perspective view of area 30 in FIG. 7;
 FIG. 31 is an enlarged and partial perspective view of area 31 in FIG. 8;
 FIG. 32 is an enlarged and partial perspective view of area 32 in FIG. 8;
 FIG. 33 is an enlarged and partial perspective view of area 33 in FIG. 9; and,
 FIG. 34 is an enlarged and partial perspective view of area 34 in FIG. 9.
 The dashed broken lines in the figures are for the purposes of illustrating portions of the electric bicycle and form no part of the claimed design.
 The dash-dot-dash broken lines are for notating enlarged views and form no part of the claimed design.
